APPARATUS FOR HEAT TREATING STEEL

Frank J. Winder, Ottawa Hills, Ohio, assignor to
 Surface Combustion Corporation, Toledo, Ohio,
 a corporation of New York

Application October 13, 1934, Serial No. 748,250
 Renewed January 20, 1936

7 Claims. (Cl. 266—5)

This invention relates to improvement in annealing furnaces of the type comprising a base on which the material is supported during annealing, and a heating hood removably supported 5 on the base to form the annealing chamber.

The object of the invention is to provide a furnace of the type indicated having a heating chamber which is rectangular in plan with an improved arrangement of combustion radiator tubes for effecting heating of a charge or pack of rectangular material.

Referring to the drawings wherein the preferred form of the invention is shown,—

Fig. 1 is a perspective view showing how the 15 combustion radiator tubes are arranged within the heating hood;

Fig. 2 is a sectional plan taken on line 2—2 of Fig. 1;

Fig. 3 is a vertical section taken on line 3—3 of 20 Fig. 1;

Fig. 4 is a perspective diagram of the piping arrangement for controlling the air and fuel supplies to the combustion tubes;

Fig. 5 is a view of one of the individual heating 25 tubes;

Fig. 6 is an enlarged sectional view of a burner associated with the intake end of the several radiator tubes, the view being taken on line 6—6 of Fig. 5;

Fig. 7 is an enlarged sectional view of an ex- 30 hauster associated with the outlet end of the several radiator tubes, and

Fig. 8 is a diagram showing the heat effect produced by the arrangement of heating tubes.

The base of the furnace is generally indicated 35 at 1. Resting on the base are a plurality of stools 2 on which the material to be annealed is supported, the material being indicated in dotted lines at M. Removably mounted on the base is 40 a heating hood generally indicated at 3. Surrounding the base is a trough 4 for receiving a depending flange 5 extending around the lower side of the hood. The trough will ordinarily be filled with sand or liquid to prevent infiltration of 45 air into the hood. During the annealing operation a non-oxidizing gas will be maintained in the hood.

Referring now more particularly to Figs. 1 and 50 6 indicates one of a series of vertically spaced heating tubes S1 disposed horizontally along one side wall 7 of the hood, the tube having a lateral portion 8 which extends along one end wall 9 of the hood, the ends of the tube being outside of the hood. A1 indicates a burner for delivering 55 fuel to the tube and B1 an exhauster for inducing

the gases to flow through the tube. 12 indicates one of another series of vertically spaced heating tubes S2 also disposed horizontally along the said side wall 7, the tube having a lateral portion 13 disposed along the other end wall 14, the ends 5 of the tube being outside of the hood. A2 indicates a burner for delivering fuel to the tube and B2 an exhauster for inducing the gases to flow through the tube.

17 indicates one of another series of vertically spaced heating tubes S3, disposed horizontally along the side wall 18 of the hood, the tube having a lateral portion 19 extending along the end wall 9, the ends of the tube being outside of the hood. A3 indicates a burner for delivering fuel 15 to the tube and B3 an exhauster for inducing the gases to flow through the tube. 22 indicates one of another series of vertically spaced heating tubes S4 also disposed horizontally along the side wall 18, the tube having a lateral portion 23 disposed along the end wall 14. A4 indicates a burner for delivering the fuel to the tube and B4 an exhauster for inducing the gases to flow 20 through the tube.

As already indicated, each heating tube has 25 its own exhauster. Each exhauster preferably comprises a Venturi tube 25 and a jet orifice nozzle 26 set to discharge into the inlet end of the tube, the Venturi tube and nozzle being supported by a fitting 27 coupled to the discharge 30 end of the heating tube. A supply pipe 28 having an ordinary shut-off valve 29 delivers fluid, such as air, under pressure to the nozzle.

The main air supply pipe is indicated at 30 and leading from this line to the several exhausters 35 is a branch supply line 31. A common waste gas flue or stack 32 is provided for each series of exhausters. Leading from the main air supply line 30 is a branch line 35 which delivers to an inspirator 36 for mixing fuel gas and air. One large 40 capacity inspirator might be used but it is preferred to use two or more of lesser capacity, two being shown. The main fuel supply line is indicated at 37, there being a branch 38 leading therefrom to the respective inspirators. A pressure 45 regulator 39, preferably one for each inspirator, reduces the gas pressure to atmospheric pressure before the gas enters the inspirator. Each inspirator discharges into its own pipe line 40 and extending from this line are two series of branch 50 pipes 18 and 38, respectively, each pipe line being provided with an ordinary shut-off valve 41. The mixture from the inspirator contains the full complement of air required by the fuel for complete combustion. 55

The 1S series of pipes delivers to the respective burners A1 of the S1 series of heating tubes and the 3S series of pipes to the respective burners A3 of the S3 series of heating tubes, it being noted that these burners are at one end of the hood. A similar arrangement is provided at the other end of the hood. Leading from the main fuel supply line 37 is another branch line 42. This line has two branches 43 running to opposite ends of the hood. Extending from each branch 43 are two series of branch pipes 1S1 and 3S3, respectively, each pipe being provided with an ordinary shut-off valve 44.

The 1S1 series of gas pipes deliver to the respective burners A1 of the S1 series of heating tubes and the 3S3 series deliver to the respective burners A3 of the S3 series of heating tubes. A similar arrangement of gas pipes is provided at the other end of the hood.

20 In the branch air line 31 leading to the exhausters is a valve 45 adapted for mechanical operation and in the branch fuel line 42 leading to the burners is a similar valve 46. These two valves are simultaneously opened and closed by any preferred means 48 responsive to the temperature inside of the heating hood, the valves being opened when there is a call for heat and closed or partly closed when there is no call for heat in the heating hood.

30 The various burners are of identical construction. In its preferred form, the burner comprises a tubular head 50 which at one end is coupled to the heating tube and forms in effect an extension thereof and which at its other end flares outwardly and is open to the atmosphere. Positioned centrally in the head is a chambered body 51, the same being centrally supported in the head by any suitable means as by two series of radially spaced screws 52 and 53 extending through the head. Adjustably mounted on the body 51 is an air shutter 54 for controlling the admission of air into the heating tube. At one end of the body 51 is a gas chamber 55 to which undiluted fuel gas is supplied under relatively low pressure. Extending from this chamber centrally of the body 51 is a fuel discharge pipe 56, the tube passing through a wall 57 adjacent one end of said body. In the said wall is a circular series of jet orifice discharge ports 58 through which the preformed mixture of air and fuel gas is discharged from an annular chamber 59 around the fuel tube 56, the mixture being supplied to said chamber by the supply tube 1S. The mixture discharged from the ports 58 serves when ignited as a constantly burning pilot flame for the fuel flowing from the fuel tube 56. By locating the wall 57 some distance inwardly from the adjacent end of the body 51, the pilot flame will not be blown out by the air flowing into the heating tube and by extending the body 51 a substantial distance into the heating tube, any initial turbulence in the air is materially reduced by the time it reaches the gas flowing from the fuel tube 56.

65 The fuel gas flowing from the fuel tube 56 and the air for supporting combustion thereof are caused to flow toward the exhaust end of the heating tube by the suction effect produced by the exhauster at said end. It will be readily apparent that the exhauster tends to cause the air and fuel gas to travel in parallel streams toward the exhauster and consequently the combustion of the fuel proceeds relatively slowly as compared, for example, with the combustion of an explosive mixture. Due to the relatively slow combustion,

the point of highest temperature in the tube is considerably remote from the burner end of the tube. Moreover, since combustion is not instantaneous but is delayed, the fuel which is not immediately burned becomes highly heated with consequent liberation of carbon, thus causing the flame in the tube to be luminous with consequent radiation of heat to the interior walls of the heating tube.

10 The distribution of heat within the tube is dependent on two factors, namely, the rate at which combustion takes place and the velocity of the gases in the tube. The rate of combustion depends upon the rapidity with which the air and gas mix and since the air and gas flow lengthwise 15 of the tube in more or less parallel streams, the rate of combustion is necessarily slow. The velocity of the gases through the tubes is controlled by the exhauster. By adjusting the valve 29 in the line 18 which delivers fluid under pressure to 20 the exhauster nozzle, the heat distribution in each tube may be readily controlled.

25 The amount of fuel permitted to flow from the various burner tubes 56 is regulated in accordance with the temperature requirements inside of the 25 heating hood, the amount of fuel being controlled by the main regulating valve 46. It is also important that the air which enters the burner end of the heating tube be varied in the same degree that the fuel delivered to the burner tubes 56 is 30 varied, otherwise there would be an excessive amount of air entering the heating tube as compared with the amount of fuel discharged from the burner tube with resultant cooling of the heating tube and general upset in the combustion 35 process. By opening and closing both of the main regulating valves 45 and 46 simultaneously, there will be no undue cooling of the heating tubes due to excess air.

40 The point of highest temperature in the various tubes will be intermediate the ends of those portions thereof that are disposed along the side walls 7 and 18 of the hood. Since two series of heating tubes are disposed along each of the said side walls and the flow of heating gases in the 45 two series is countercurrent, the point of maximum heat intensity is midway the ends of the respective side walls, or in other words, more heat is applied to the middle portion of the adjacent vertical side of the material M than is 50 applied near the vertical corners thereof. As a consequence of such heating, the corners of the material do not tend to become overheated. Moreover, since the flow of heating gases is 55 countercurrent to the two series of tubes along each of the end walls 9 and 14 of the hood, the point of maximum heat intensity at such end is also midway the end of said walls. The intensity of the heat at the ends of the material is, of course, much less than at the long side thereof 60 but nevertheless such heat as is available is applied to the middle portion thereof.

65 The chart comprising Fig. 8 illustrates diagrammatically the overlapping which occurs in the heat effect of the heating tubes, and the location of such heat effects with respect to the heated material M. In the diagram, the dot and dash line a1—a2 represents a heating tube of the S1 series. The dash line b1—b2 represents a heating tube of the S3 series. The dotted line c1—c2 represents a heating tube of the S2 series and the two-dot and dash line d1—d2 represents a heating tube of the S4 series. The progressive increase and decrease in heat in the various heating tubes is indicated graphically by curved lines 70 75

similar to the lines representing the heating tubes. Thus the curved dot and dash line, beginning at the point *ax* on the line *a1—a2*, and extending to the point *ay* on the line *a1—a2* indicates graphically by its distance from the line *a1—a2* the intensity of the heat in the tube.

Similarly, the curved lines *bx—by*, *cx—cy*, and *dx—dy* indicate respectively the intensity of heat in tubes *b1—b2*, *c1—c2* and *d1—d2*. In order to show the overlapping of the heat effects, the area between the tube lines *a1—a2*, *b1—b2*, *c1—c2*, *d1—d2*, and the respective heat curve lines *ax—ay*, *bx—by*, *cx—cy*, and *dx—dy*, are vertically and horizontally cross sectioned, there being only one set of section lines for a single area. Obviously where these sectional areas overlap the composite heating effect is clearly shown by the one overlapped section. It will be noted that the heat curve line *ax—ay* belonging to the tube *a1—a2*, crosses at the point *m* the heat curve line *cx—cy* belonging to the tube *c1—c2*. This point *m* occurs at the transfer center line of the pile of material *M* and indicates that a maximum heat effect will take place at this point, for the side of the pile in question. On the other side of the pile, the heat curve line *bx—by*, and *dx—dy* crosses the point *m'*, which is also on the transverse center line of the pile of material *M*. Similarly, the points *n* and *n'* represent the points of maximum heat effect on the ends of the material and are located on the longitudinal center line of the pile.

What I claim as new and desire to secure by Letters Patent is:

35. 1. A furnace comprising, in combination, walls forming a heating chamber which is rectangular in plan, two sets of heating tubes, one of said sets being disposed along one side wall and the other along the opposite side wall of the chamber, the tubes of both sets each having a lateral portion disposed along one and the same end wall of the heating chamber, two other sets of heating tubes, one of these sets being disposed along the said one side wall and the other along 40 said opposite side wall, the tubes of both of the last mentioned sets each having a lateral portion disposed along the other end wall of the chamber.

45. 2. A furnace comprising, in combination, walls forming a heating chamber which is rectangular in plan, two sets of heating tubes, one of said sets being disposed along one side wall and the other along the opposite side wall of the chamber, the tubes of both sets each having a lateral portion disposed along one and the same end wall of the chamber, two other sets of heating tubes, one of these sets being disposed along the said one side wall and the other along the said opposite side wall, the tubes of both of the last mentioned sets each having a lateral portion disposed along 50 the other end wall of the chamber, and means for supplying heating gases to one end of each of said tubes.

55. 3. A furnace comprising, in combination, walls forming a chamber which is rectangular in plan, two sets of heating tubes, one of said sets being

disposed along one side wall and the other along the opposite side wall of the chamber, the tubes of both sets each having a lateral portion disposed along one and the same end wall of the chamber, two other sets of heating tubes, one of these sets being disposed along the said one side wall and the other along the said opposite side wall, the tubes of both of the last mentioned sets each having a lateral portion disposed along the other end wall of the chamber, means for supplying heating gases to one end of each of said tubes, and means independent of said means for controlling the rate of flow of the gases through the respective tubes.

4. A furnace comprising, in combination, walls forming a heating chamber which is rectangular in plan, two sets of heating tubes, one of said sets being disposed along one side wall and the other along the opposite side wall of the chamber, the tubes of both sets each having a lateral portion disposed along one and the same end wall of the chamber, two other sets of heating tubes, one of these sets being disposed along the said one side wall and the other along the said opposite side wall, the tubes of both of the last mentioned sets each having a lateral portion disposed along the other end wall of the chamber, means for supplying heating gases to one end of each of said tubes, said ends being open to the atmosphere, and regulable means for producing a partial vacuum at the other end of the respective tubes for controlling the admission of air into the fuel receiving end thereof.

5. A furnace comprising, in combination, walls forming a heating chamber which is rectangular in plan, a plurality of heating tubes inside of said chamber, each tube extending along two successive walls of the chamber and projecting from the chamber through the next succeeding wall.

6. A furnace comprising, in combination, walls forming a heating chamber which is rectangular in plan, two sets of heat radiating tubes inside of said chamber and each tube having a bend intermediate its ends, the bend of the tubes of one set being adjacent one corner and the bend of the tubes of the other set being at the diagonally opposite corner of the chamber.

7. A furnace comprising, in combination, walls forming a heating chamber, heating tubes penetrating the walls and extending within the chamber, means arranged at the exit ends of the heating tubes for controlling gaseous flow through the tubes, such means including piping for fluid under pressure, means arranged at the intake ends of the heating tubes for supplying fuel gas, such means including a piping for fuel gas, two valves arranged, one in the piping for said fluid, the other in said fuel gas piping, and common means for shifting said valves in response to variations of temperature in the heating chamber.

FRANK J. WINDER.
